FLYING TOY

Davey L. Langston, 3616 Mount Vernon,
Fort Worth, Tex. 76103

Filed Feb. 25, 1975, Ser. No. 552,941

Term of patent 14 years

Int. Cl. D21—02

U.S. Cl. D34—15 W

FIG. 1

FIG. 2

FIG. 3

FIG. 4

FIG. 1 is a front elevational view of a flying toy showing my new design;

FIG. 2 is a side elevational view thereof;

FIG. 3 is a top plan view thereof; and

FIG. 4 is a bottom plan view thereof.

I claim:

The ornamental design for a flying toy, substantially as shown.
